BUILDING CONSTRUCTION

John Wright Warren, Knoxville, Tenn.

Application October 15, 1934, Serial No. 748,417

15 Claims. (Cl. 72—68)

My invention relates to building constructions and more particularly comprises certain novel types of elements adapted to be precast and associated to form a joist-supported floor construction, the arrangement of such elements in a floor construction, and a novel method of making certain of the elements.

An important aspect of the invention is a novel type of joint by which abutting slabs of precast material are adapted to be associated in a floor and joist construction of superior strength, integrity and permanence. In a full, preferred form of embodiment the abutting slabs and the cooperating surfaces of the joist are specially formed so that the slabs and the joist cooperate to define a joint space acting as a keyway for a filler of mortar, cement or grouting acting as a key to prevent relative movement of the slabs and joist.

An important object of the invention is to provide a slab and joist construction capable of being inexpensively manufactured without special equipment except appropriate molds, and capable of being readily assembled by comparatively unskilled labor.

A further object of the invention is to provide a slab and joist arrangement including reinforced joints resulting in a substantially monolithic floor and support construction in which movement of the slabs relative to each other and relative to the joist is effectively prevented.

A special feature of the invention resides in providing joists and slabs formed to provide the novel and efficient type of joint broadly explained above without requiring the slabs and joist to be provided with shoulders which are difficult to form by a casting operation. In other words, the special form of the elements contemplated by the present invention is consistent with rapid and easy manufacture according to methods already well known.

The invention contemplates further a novel process of casting the joist elements whereby these elements are capable of being quickly and inexpensively made with internal reinforcing means and an accurately formed external surface well adapted to support the cooperating slabs and cooperating with them in forming a close-fitting assembly providing an originally open joint capable of receiving cementitious material without leakage, or without excessive leakage, to form the key mentioned above.

An additional object of the invention is to provide slab elements having specially formed edges adapted to cooperate to provide a trough-like

open groove having a substantially closed bottom, so that plastic cementitious material introduced into the open trough to bond the slabs together will be retained therein without loss through leakage, and a closely related object is to form the trough-defining edges of cooperating slabs with means for supporting joint reinforcing elements in a predetermined desirable relation to the height or thickness of the slabs, requiring practically no exercise of skill or judgment on the part of the installing workman.

Various additional objects are contemplated by the invention, and other advantageous features are inherent in it, all of which will become more apparent as the following description of a preferred form of embodiment proceeds.

In the accompanying drawing which forms part of this application for Letters Patent and which, in conjunction with the following description, discloses a preferred embodiment of the invention,

Figure 1 is a sectional view through a joist and a portion of two slab elements supported by the joist and bonded thereto in accordance with the principles of the present invention;

Fig. 2 is a sectional view through the slabs shown in Fig. 1, taken at a right angle thereto, and showing a portion of the joist in side elevation;

Fig. 3 is a section taken through the molding equipment showing a plurality of mold boxes in which the joists are being made; and

Fig. 4 is a perspective view of a corner of one of the floor slabs showing the two novel edge formations contemplated by the invention.

It is to be understood that I regard the invention as of broad scope, including essentially any means as defined by the appended claims for achieving the objects indicated hereinabove. The invention is thus not to be regarded as limited to the exact type of specific elements which are explained by way of illustration in this specification. Such terms as "joist", "floor slab" and the like are intended to include additional analogous building construction elements to which the invention is obviously applicable.

Referring now to Fig. 1, the embodiment of the invention there shown includes a joist 1, preferably precast as will be later explained, and reinforced by a pair of spaced longitudinal elements 2, 2 and a series of transverse tie wires or the like 3, looped around and connecting the longitudinals 2. The upper, or floor supporting surface 4 of the joist may be made somewhat thicker than the central portion of the joist, and the bottom

part of the joist may be similarly thickened, for the usual purpose of economizing in material and providing wide bearing surfaces.

The floor-supporting surface 4 is provided with a longitudinal, central channel 5, which may be relatively shallow and which may have outwardly flaring sides, as shown.

The slabs 6 are conveniently all made alike, and as shown in Fig. 4, each slab comprises a relatively flat body having the novel types of end wall which will now be described.

The end wall 7 of each slab is intended to be placed over the channel 5 of a joist and there cooperate with the similar end wall 7 of another slab spaced somewhat from it to provide an open joint as shown in Fig. 1. The end wall 7 therefore comprises an upper margin 8 and a lower margin 9, both of which may lie in the same plane and be normal to the top and bottom surfaces of the slab. The margins 8 and 9 are separated by an indentation 10 which may take the form of the groove or channel as shown in Fig. 4. Preferably each end wall 7 is provided with a plurality of these indentations, for example two separated by a sort of lug 11 which may be flush with the margins 8 and 9, and which has end portions 12 which preferably constitute abrupt ends of the indentations 10.

It will be understood that each slab is conveniently provided with two opposite, similar end walls 7. Each slab may be rectangular in plan, and its remaining two end walls are each preferably formed as shown at 13 in Fig. 4. This formation comprises an upper margin 14 and a lower margin 15, each of which may be normal to the broad top and bottom surfaces of the slab and both of which lie in parallel spaced planes, the lower margin 15 being extended outwardly an appreciable distance beyond the plane of the upper margin 14. The margins 14 and 15 are separated by an indentation 16 which may take the form of the groove or channel shown in Fig. 4. Each end wall 13 is preferably provided with a plurality of indentations 16, for example the two shown in Fig. 4, and these indentations are separated by a sort of lug 17 which constitutes a beveled connection for the margins 14 and 15. The side walls 18 of the lug 17 are preferably formed to constitute abrupt ends for the indentations 16, this phase of this end wall construction being analogous to the relationship of the parts 11, 12 and 10 as explained in the foregoing description of the wall 7.

A plurality of slabs formed to include the essential features of the end wall constructions just explained is assembled with joists in the relationship shown in Figs. 1 and 2, that is, end walls 7 of adjacent slabs are spaced apart slightly over the channel 5 of the joist, with the edge margins 15 of the bottom surfaces resting on the floor-supporting surface 4 of the joist, and the end walls 13 of the slabs are placed quite close together and extend right-angularly to the joist, as shown in Fig. 2. It will be observed that the cooperating lower margins 15 of the end walls 13 are separated by a very slight space.

Joint reinforcing elements 19 are placed in the joint shown in Fig. 2 defined by end walls 13, and are supported in the joint by resting on the cooperating lugs 17. Similar reinforcing elements 20 are then laid in the joints defined by the end walls 7 and are supported by resting on the reinforcing elements 19, as shown in Fig. 1.

Plastic cementitious material, such as Portland cement, mortar, grouting or the like, is then

poured into both joints. In the joint of Fig. 1 the cementitious material fills the channel 5 and the rest of the joint up to the top surfaces of the slabs. In the joint of Fig. 2 the cementitious material fills the entire joint up to the top surfaces of the slabs, little or none being permitted to escape through the closely spaced cooperating lower margins 15.

It will be evident from Fig. 1 that the cementitious material in the joint there shown constitutes, when completely set, a key 21 which will prevent lifting of either slab, or any longitudinal or lateral movement thereof, securely and permanently bonding the slabs and the joist together. It will also be evident that the key 22, similarly formed in the joint of Fig. 2 will prevent lifting of either slab or horizontal movement thereof. It will be obvious that these movements are prevented by the reaction of the various shoulders formed in the joints with the key which completely fills the joint and abuts the various shoulders. The shoulders are of course the end walls 12 and 18 of lugs 11 and 17 and the surfaces of the indentations 10 and 16.

It will be observed further that the reinforcing elements 19 and 20 are securely embedded in their respective joints, so that the joints are made unusually strong and the permanence of the bond provided by the keys 21 and 22 is assured.

It is important that the slab-supporting surface 4 of the joist 1 be accurately plane and smooth, lest the cementitious material which is to form the key 21 be largely lost by leakage through the abutting surfaces of the slabs and joists. To obtain accurate placement of the channel 5 and the required accurate smoothness and planeness of the surfaces 4, I cast the joist as shown in Fig. 3. The surface 4 is formed at the bottom of the mold, where it is easy to provide a smooth and plane bottom mold wall 23. A filler 24 is used to form the channel 5. The reinforcing assembly, designated generally 25, and comprising the longitudinals and the connecting tie, is introduced into the mold with a portion of the mix. The mix may be tamped in place if desired and the extending end of the reinforcing assembly 25 may then be positioned upright in the mold cavity centrally thereof. It remains supported in this central position by the portion of the mix which surrounds the lower part of the reinforcing assembly. The balance of the mix is then introduced into the mold and levelled off at the top. After hardening, the mold is stripped and the result is a precast joist having an accurately formed slab-supporting surface 4 and an accurately centrally positioned reinforcing assembly 25.

It is to be observed that the branching arms of the tie wire 3 which extend through and reinforce the thickened, floor-supporting portion of the joist comprise in effect a pair of legs on which the reinforcing assembly 25 stands in the mold, contributing materially to its stability while the finishing quantity of mix is being introduced into the mold. The reinforcing assembly 25 may be formed in any convenient manner, and comprises, in the form which I prefer to employ, relatively thick rods 2, and thinner wires 3 connecting the rods 2 and constituting the end legs just described.

The invention has been described in terms of a specific embodiment, but is capable of being embodied in other and further modified forms. The explanation of one embodiment in this specification is to be taken as illustrative only. Various changes, not affecting the spirit or principles of the invention, will suggest themselves to persons

skilled in the art, and all such changes, to the extent that they incorporate the principles of the invention as defined by the appended claims, are to be deemed within the scope and purview of 5 such principles and claims.

I claim:

1. A building construction comprising a joist having an upper surface provided with a channel, a pair of slabs resting on the joist with a portion of their adjacent edges spaced apart and overlying a portion only of the channel, and a filler of cementitious material in the space between the slabs and in the channel under the edges of the slabs bonding the slabs to the joist. 10
2. A building construction comprising a joist having an upper surface provided with a channel, a pair of slabs resting on the joist with a portion of their adjacent edges spaced apart a distance less than the width of the channel and overlying a portion only of the channel, and a filler of cementitious material in the space between the slabs and in the channel under the edges of the slabs bonding the slabs to the joist. 15
3. A building construction comprising a joist having an upper surface provided with a channel, a pair of slabs resting on the joist with a portion of their adjacent edges spaced apart a distance less than the width of the channel and overlying the marginal portions only of the channel, 20 and a filler of cementitious material in the space between the slabs and in the channel under the edges of the slabs bonding the slabs to the joist. 25
4. A building construction comprising a joist having an upper surface provided with a channel, a pair of slabs resting on the joist with a portion of their adjacent edges spaced apart and overlying a portion only of the channel, said edge of one of the slabs being provided with an indentation constituting a lateral enlargement of the 30 joint formed by said edges, and a filler of cementitious material filling the channel and the joint, including the lateral enlargement, bonding the slabs to the joist. 35
5. A building construction comprising a joist having an upper surface provided with a channel, a pair of slabs resting on the joist with a portion of their adjacent edges spaced apart and overlying a portion only of the channel, said edge of each of the slabs being provided with an indentation constituting lateral enlargements of the 40 joint formed by said edges, and a filler of cementitious material filling the channel and the joint, including the lateral enlargements, bonding the slabs to the joist. 45
6. A building construction comprising a joist having an upper surface provided with a channel, a pair of slabs resting on the joist with a portion of their adjacent edges spaced apart and overlying a portion only of the channel, said edge of each of the slabs being provided with an indentation spaced above the bottom surface of the slab and constituting lateral enlargements of the joint 50 formed by said edges, and a filler of cementitious material filling the channel and the joint, including the lateral enlargements, bonding the slabs to the joist. 55
7. A building construction comprising a joist having an upper surface provided with a channel, a pair of slabs resting on the joist with a portion of their adjacent edges spaced apart and overlying a portion only of the channel, said edge of one of the slabs being provided with an indentation constituting a lateral enlargement of the joint formed by said edges, a portion of the material of the slab being extended into said indenta- 60
8. A building construction comprising a joist having an upper surface provided with a channel, a pair of slabs resting on the joist with a portion of their adjacent edges spaced apart and overlying a portion only of the channel, said edges of the slabs being provided with indentations constituting lateral enlargements of the joint formed by said edges, a portion of the material of each slab being extended into the indentation in said slab to form an end wall of 65 said indentation, and a filler of cementitious material filling the channel and the joint, including the lateral enlargements, bonding the slabs to the joist. 70
9. A building element comprising a slab having an end wall adapted to be juxtaposed with and bonded to the similar end wall of a similar element, said end wall having a lower edge which extends outwardly beyond its upper edge, and said end wall including a narrow beveled portion connecting said edges, at substantially the center only of the end wall, and having an indentation at opposite sides of said bevelled portion for receiving mortar or the like. 75
10. A building element comprising a slab having an end wall adapted to be juxtaposed with and bonded to the similar end wall of a similar element, said end wall having a lower edge which extends outwardly beyond the upper edge, the end wall including a bevelled portion connecting said edges and including an indented portion adjacent said connecting portion. 80
11. A building element comprising a slab having an end wall adapted to be juxtaposed with and bonded to the similar end wall of a similar element, said end wall having a lower edge which extends outwardly beyond the upper edge, the end wall including a bevelled portion connecting said edges and including a pair of indented portions, one on each opposite side of said connecting portion. 85
12. A building construction comprising a pair of slabs having faced end walls, each of said slabs having the lower edge of its said end wall extended outwardly beyond the upper edge of said wall and each wall being provided with a bevelled portion connecting said edges and an indentation adjacent the bevelled portion, the lower edges of the faced walls being placed close together and the upper edges of said walls being more widely separated, whereby a trough joint is provided, in combination with a reinforcing element resting on and centrally positioned by adjacent faced bevelled portions and a filler of cementitious material filling the joint above and below the reinforcing element and bonding the slabs together. 90
13. A building construction as claimed in claim 12, in which reinforcing rods are provided in the joints at right angles to the joints specified in the claim, and in which said rods rest on and are supported by the reinforcing elements specified in the claim. 95
14. A building construction including a plurality of building elements each comprising a slab having a substantially flat end wall broken by a pair of lengthwise indentations each entering from and open to an opposite edge of the end wall, said end wall including an unindented portion constituting a lug separating the indentations, said elements being positioned with said 75

tion to form an end wall thereof, and a filler of cementitious material filling the channel and the joint, including the lateral enlargement, bonding the slabs to the joist. 65

edges spaced apart to form an open joint, and a filler of cementitious material filling said joint and bonding the elements together.

15. A building construction including a plurality of building elements each comprising a slab having opposite end walls, each of said walls including a substantially straight, plane portion connecting the top and bottom edges of the wall and an indented portion immediately adjacent to

and on each opposite side of the plane portion, each indented portion entering from and being open to an opposite end edge of the end wall, said elements being positioned with said top edges spaced apart to form an open joint, and a filler of cementitious material filling said joint and bonding the elements together.

JOHN WRIGHT WARREN.
